(57) **CLAIM**

I claim the ornamental design for a footwear article, as shown and described.

DESCRIPTION

FIG. 1 is a first side view of a footwear article; FIG. 2 is a second side view of the footwear article of FIG. 1; FIG. 3 is a first side, front perspective view of the footwear article of FIG. 1; FIG. 4 is a first side, rear perspective view of the footwear article of FIG. 1; FIG. 5 is a front view of the footwear article of FIG. 1; FIG. 6 is a rear view of the footwear article of FIG. 1; FIG. 7 is a top view of the footwear article of FIG. 1; and, FIG. 8 is a bottom view of the footwear article of FIG. 1. The dashed broken lines depict portions of the footwear article that form no part of the claimed design. The dot-dash broken lines depict the boundaries of the claimed design and form no part thereof.

1 Claim, 8 Drawing Sheets
